UNITED STATES PATENT OFFICE

CHARLES E. JONES, OF PHILADELPHIA, PENNSYLVANIA

SKIVING MACHINE

Application filed March 8, 1927. Serial No. 173,622.

My invention relates to skiving machines and more particularly to a machine adapted to shave the edges of leather in order that such edges may be folded back upon themselves to produce a seam no thicker than the body of the leather.

I am aware that skiving machines have been in use for a number of years but, to the best of my knowledge, no machine has ever been produced which will skive the edges of a piece of leather whose outline is irregular.

One of the objects of my invention is to provide a machine which will skive the edges of a piece of leather regardless of the irregularity of its outline.

In the manufacture of certain styles of shoes, it is customary to cut holes in the leather and, in some cases, to place a piece of different colored leather behind such openings in order to provide a contrast of color. In the better grade of shoes, it is customary to skive and fold the edges of the leather around these openings in order that the raw edges of the leather will not show and, until my machine was produced, it was necessary to do such skiving by hand.

Another object of my invention is to provide a machine which will skive the edges around apertures in leather in order that such edges may be folded over to form seams no thicker than the body of the leather.

Still another object of my invention is to provide a skiving machine which will be compact and occupy but little bench or floor space and which will be capable of producing a large quantity of work with the consumption of a comparatively small amount of power.

These objects, and other advantageous ends which will be described hereinafter, I attain in the following manner, reference being had to the accompanying drawings in which

Figure 1 is a front elevation, and

Figure 2 a top plan view of a skiving machine embodying my invention.

Figure 3 is an elevation of the left hand end of the machine shown in Figures 1 and 2, and

Figure 4 a fragmentary sectional view, partly in full, taken substantially on line 4—4 on Figure 1.

Figures 5, 6 and 7 are enlarged fragmentary sectional views, partly in full, showing certain details of construction.

Figure 8 is a fragmentary plan view, Figure 9 a fragmentary front view, and

Figure 10 a fragmentary end view of the skiving mechanism, drawn to an enlarged scale and showing a piece of leather in the machine.

Figure 11 is a fragmentary view showing the method of making a square shouldered skive; the thickness of the leather being greatly exaggerated.

Figure 12 is a view similar to Figure 11 but showing a method of making a beveled skive; the thickness of the leather and the tilt of the cutting disk being exaggerated.

Figure 13 shows a piece of leather having skived edges around an aperture therein.

Referring now more in detail to the drawings, the machine has a base 15, from which a main frame 16 extends upwardly and has a U-shaped bearing 17 secured thereto in which is rotatable a shaft 18 carrying a loose pulley 19 and fixed pulleys 20 and 21 between the two parts of the bearing. One end of shaft 18 extends beyond bearing 17 and has fixed thereon a pulley 22 abutting the end of the bearing and a beveled gear 23 abutting the pulley. Gear 23 meshes with a beveled gear 24 fixed to a vertical shaft 25 rotatable in a divided bearing 26 secured to the side of main frame 16. Between the two bearing portions, a pulley 27 is fixed to shaft 25 and carries a belt 28 which also engages a pulley 29 fixed on a spindle 30 rotatable in a divided bearing 31. A cutting disk 32 is secured to the lower end of spindle 30 and a collar 33 is fixed to its upper end, preferably by having a tapered pin inserted through holes in the shaft and collar respectively.

A guard bearing 34 is journaled on spindle 30 immediately below collar 33 and, when in its lowermost position, rests on the top of bearing 31. An extension 35 is formed on bearing 34 and has an adjusting screw 36 rotatable therein and threaded into the top of bearing 31. Screw 36 is held against axial movement through bearing 34 by means of a shoulder 37 and a collar 38 disposed at either

side of extension 35. It is evident that turning screw 36 to the left will raise guard bearing 34, spindle 30 and cutting disk 32 and that turning screw 36 to the right will lower these parts.

5 A bifurcated bracket 39 (see Figure 4) is secured to the front of frame 16 and has hinged in its outer end an arm carrying a bearing 40 in which a shaft 41 is rotatable. 10 A pulley 42 is fixed to one end of shaft 41 while the other end of the shaft is bifurcated and forms a part of a universal joint 43. A shaft 44 has a part of universal joint 43 formed on one end and a pinion 45 fixed to the 15 shaft adjacent thereto. At the other end of the shaft is fixed a feed roller 46 the shaft being rotatable in a bearing 47 and in a bearing 48.

20 A belt 49 encircles pulleys 22 and 42 and the latter pulley is normally held out of contact with belt 49 by means of a compression spring 50 encircling a rod 51 between base 15 and a collar 52 fixed to rod 51; one end of rod 51 being secured to an extension 53 on 25 bearing 40 and its other end extending through base 15 and being connected to a pedal (not shown). It is evident that, by depressing the pedal attached to rod 51, spring 50 will be compressed and pulley 42 30 brought into contact with belt 49 and shafts 41 and 44 rotated.

35 Pinion 45 meshes with a gear 54 secured to a shaft 55 rotatable in bearings 56 and 57 and having a supporting wheel 58 secured to its left end viewed as in Figure 1. Shaft 55 is held against longitudinal movement by gear 54 abutting one end of bearing 56 and a collar 59 abutting its other end; gear 54 and collar 59 being secured to shaft 55 by 40 means of suitable set screws. It is evident that, by loosening the set screws, shaft 55 may be moved longitudinally through bearing 56. A bolt 60, see Figure 4, is rotatable in frame 16, which has a boss 56^a extending 45 from its face at this point, and is threaded into the rear side of bearing 56 at a point adjacent gear 54 so that wheel 58 may be raised and lowered without causing shaft 55 to bind in bearing 56 or moving gear 54 out 50 of mesh with pinion 45.

55 Bearing 57 is provided with a downwardly extending neck 61 which is inserted in the bifurcated end of a stem 62 and rockably held therein by means of a countersunk headed screw 63. Stem 62 is slidably mounted in a post 64 mounted on base 15 and provided with a transverse bore in which a cam shaft 65 is rotatable. Cam shaft 65 supports stem 62 and has a crank 66 secured to its rear end which is provided at its outer end with a pin 67 engaging a slot 68 in a lever 69 rockably mounted in a bearing 70 secured to base 15. A pin 71, slidably in a slot in the other end of lever 69, is secured in the top end of a rod 72 extending through base 15 and hav-

ing a pedal (not shown) connected to its lower end.

This pedal is connected in such a manner that depressing one of its ends will lower rod 72 and raise the other end of lever 69, consequently raising wheel 58 against feed roller 46, while depressing the opposite end of the lever will cause cam face 73 (see Figure 6) in cam shaft 65 to move into its uppermost position and allow a spring 74, which has its ends secured to post 64 and neck 61 respectively, to move bearing 57 downwardly. Lever 69 and crank 66 are so proportioned that they will remain in their extreme positions until moved therefrom by the action of rod 72.

20 A belt 75 is connected to a suitable source of power and engages pulley 19 when the machine is not in operation. When it is desired to operate the machine, belt 75 is thrown onto pulley 20 and cutting disk 32 is rotated at a high speed through the action of shaft 18, gears 23 and 24, shaft 25, belt 28, and spindle 30. A piece of leather 76, having an aperture 77, may be placed on supporting wheel 58 with the aperture disposed between the wheel and cutting disk 32 and with the edge of the aperture hooked over a foot 78 secured to bearing 48 and conforming to a sector of the periphery of the wheel 58. 95 The pedals are depressed to raise supporting wheel 58 to the position shown in the drawings and to bring pulley 42 into engagement with belt 49 so that supporting wheel 58 and feed roller 46 will be rotated and tend to feed leather 76 toward cutting disk 32. The surface of feed roller 46 is knurled to afford traction on the leather but should not be roughened sufficiently to mar the finished surface of fine leather.

100 The center of the rim of supporting wheel 58 is preferably on a line with the center line of cutting disk 32 so that the skive made in leather 76 will be approximately one half the width of the supporting wheel. Feed roller 46 engages the top of the leather and presses it firmly against supporting wheel 58 as well as feeding the leather toward cutting disk 32. The peripheral speed of feed roller 46 is the same as the peripheral speed of supporting wheel 58 as their diameters are proportional to the diameters of pinion 45 and gear 54 respectively.

105 Feed roller 46 is pressed downwardly by a leaf spring 79 (see Figure 5) mounted on a bracket 80 secured to bearing 48 and the tension of the spring is regulated by means of a thumb screw 81 threaded through the top of bracket 80 and engaging the top of the spring. This method of forcing roller 46 against the leather provides an even pressure and allows for inequalities in thickness. Bearing 48 is mounted on frame 16 by means of an extension 82 (see Figures 1 and 2) provided with a slot 83 through which a bolt 110

84 extends and is threaded in frame 16. Slot 83 is provided in order that bearing 48 and its associated parts may be moved outwardly as will be later described. Shaft 44 is movable vertically in bearing 48 which is provided with a cap 85 resting on the top of shaft 44 and tending to hold same in its lower position by the action of spring 79; cap 85 being held against lateral movement by fitting between the sides of bearing 48. It will be noted that shaft 44 is reduced in diameter adjacent roller 46 and that bearing 48 and cap 85 are bored to accommodate this reduced portion so that shaft 44 is held against axial movement relatively to bearing 48 by the shoulders thus formed on the shaft and in the bearing abutting each other and by the end of roller 46 abutting the end 86 of bearing 48.

End 86 of bearing 48 is normally in line with the transverse centerline of wheel 58 and its lower edge extends below roller 46 and acts as a guide for the edge of the leather which is being skived. Foot 78 is secured to or formed on bearing 48 so that its left hand edge, as in Figure 8, coincides with end 86 and the top of foot 78, as well as the adjacent corner of bearing 48, is rounded so that the leather may be readily led from the top of foot 78 along end 86 to the cutting disk 32, as shown at 87 in Figure 8. In order that spring 79 will not press feed roller 46 against the supporting wheel when there is no leather interposed between them, I provide an extension 88 on bearing cap 85 and thread therethrough a thumb screw 89, see Figure 9, the end of which bears against bearing 48. If it were not for thumb screw 89, it would be difficult to introduce leather between feed roller 46 and supporting wheel 58.

As feed roller 46 must move vertically to allow for different thicknesses of leather, bearing 47 must be so mounted that it will swivel slightly to accommodate the vertical movement of shaft 44. This is accomplished by making the rear end of bearing 47 cylindrical, cutting fine threads thereon and then screwing the bearing into a projection 47^a formed on frame 16.

Leather 76 is bent downwardly along the face 90 of supporting wheel 58 at a point adjacent cutting disk 32 so that the width of the skive will be equal to approximately one half the width of wheel 58. This is accomplished by a U-shaped guide member 91 bolted to the top of bearing cap 85 and having its lower portion 92 disposed near face 90 of the supporting wheel. The bottom of portion 92 is tapered from the front to rear and the bottom part of its free end rounded, as shown in Figure 9, in order that there will be no square edges to mar the leather being skived or to impede its progress through the machine. The bolt, which secures guide member 91 to bearing cap 85, passes through a slot 93 in the top of the guide member, see Fig-

ure 8, so that the distance between the end of portion 92 and face 90 of supporting wheel 58 may be varied to accommodate different thicknesses of leather.

In order that the leather being skived will be kept out of contact with cutting disk 32, except at the point where the skiving is done, I provide a flat guard 94 adjacent the under side of disk 32 and supported by a rod 95 secured to guard bearing 34 so that when disk 32 is raised or lowered, by means of guard bearing 34 and adjusting screw 36, guard 94 will move with it.

When a piece of leather is fed through the machine as above described, a shaving of a width equal to the distance between face 90 and end 86 will be cut from the leather so that, when the portion of leather bent over by guide member 91 is raised to the same plane as the skived portion, a substantially square shouldered skive, such as is shown in Figure 11, will be formed. In skiving the edges around an aperture in a piece of leather, foot 78 will prevent the leather from being drawn too far into the machine and end 86 will guide the material so that a skive is made in the proper location. With this arrangement, the edges of an aperture may be quickly and neatly skived regardless of the size or shape of the aperture, which operation has heretofore been impossible.

Assuming that the machine is supplied with power and that it is desired to skive the edges of an opening in a piece of leather, the pedal on rod 72 should be operated to lower wheel 58, the leather inserted between wheel 58 and roller 46 until the edge of the aperture can be hooked over foot 78, the pedal is then operated to raise wheel 58 into contact with the leather pressing the same against roller 46. The pedal on rod 51 is then depressed and pulley 42 brought into engagement with belt 49 so that rotation is imparted to roller 46 and wheel 58 thereon feeding the leather toward disk 32.

Remembering that guide 91 has bent the leather against the face 90 of wheel 58 and that the edge of the aperture cannot move beyond end 86, it is apparent that the slice will be cut off that portion of the leather on the periphery of the wheel 58 as it is fed against disk 32. The operator works the leather over foot 78, keeping the portion next to disk 32 against end 86 while allowing roller 46 and wheel 58 to feed the leather toward disk 32. It is to be understood that the leather is thin and flexible and can easily be distorted by the operator in working same over foot 78 and that guard 94 deflects the leather away from cutting disk 32 as fast as it is skived. In this manner, the edges of an aperture may be readily skived, regardless of the contour of the aperture. In skiving the outer edges of a piece of leather, it is

held against end 86 as it is fed between roller 46 and wheel 58.

In this connection it is to be borne in mind that the space on both sides of the wheel 58 immediately beneath the disc 32 is clear and unobscured permitting the leather to be turned about by the attendant as may be desired. In fact, the machine will almost work automatically after the opening in the leather has been hooked over the member 78. When the skiving of the leather along one side of an aperture such as is shown in Figure 13 has been completed, the leather will be prevented from advancing further by the foot 78.

The pull on the leather by the wheel 58 and the roller 46 will, under these circumstances, tend to cause the leather to be rotated to the right (viewing the machine as presented in Figure 1). This tendency is materially aided by the peculiar knurling of the roller 46 which is such as to tend to pull the leather toward the end or shoulder 86. This shoulder, as set forth above, prevents further progress of the edge being operated upon by the disc 32, but after the edge has been skived the leather may fully turn about the foot 78 for the reasons set forth above. The unfinished side of the leather is presented to the roller 46 and the leather is pressed downwardly over the edge of wheel 58 by the guide member 91.

With the freedom provided as outlined above, the leather may be turned at will by the attendant without in any manner marring or injuring the leather. In consequence, an aperture of any shape and an edge however irregular may be skived without injuring the work. Also, owing to the tendency of the knurled roller 46 to move the edge being operated on laterally thereof toward the end 86, there will be a tendency of the edge to be fed to the right after it passes this end and a consequent drawing of the next edge of the aperture to be operated on, into position, and so on.

In this connection, the shape of the foot 78 as shown in dotted lines in Figure 10 should be noted. The foot extends downward in conformity to the periphery of the wheel 58, and therefore presents no obstruction to the turning of the leather.

With regard to the specific knurling of the roller 46 by which a feed is obtained tending to maintain the edge of the leather being skived against the end shoulder 86, it will be seen, by examination of Figures 1, 4, 5 and 9 that the ridges of the knurling are in the nature of spirals 46^a the course of which is upward toward the end 86, as viewed from the front. In consequence, as the roller 46 is rotated clockwise and the wheel 58 counter-clockwise considering the rollers as viewed in Figure 3 the ridges on wheel 46 will tend to force the leather toward the right as viewed in Figure 1, thus rendering the skiving action somewhat automatic as to the maintenance of

the edge being skived against the end 86, and as to the turning of the leather when the end of one edge is reached.

Sometimes it is desirable that the skive be tapered or beveled, as shown in Figure 12, and to attain this end I mount bearing 31 on a support 96 which is held in selected positions by means of a bolt 97 passing through a slot 98 and being secured in frame 16; bearing 31 being pivoted to main frame 16 by a pin 99 disposed opposite the center line of spindle 30 and near the center of the lower half of bearing 31. By loosening bolt 97, bearing 31 and support 96 may be swung on pin 99 and thus tilt cutting disk 32, relatively to supporting wheel 58, and thus allow a beveled cut being taken from the edge of the leather, as shown in Figure 12.

By tilting spindle 30, the center of the cutting disk is moved from the center line of supporting wheel 58. The set screws in gear 54 and collar 59 may be loosened and shaft 55 moved longitudinally to bring supporting wheel 58 into effective position relative to disk 32. Bolt 84 may then be loosened and bearing 48 moved longitudinally to bring feed roller 46 into position relative to wheel 58; pinion 45, being of greater width than gear 54, does not need to be moved. While the width of a square shouldered skive is determined by the distance between end 86 of bearing 48 and face 90 of wheel 58, the width of a beveled skive is also determined by the tilt of disk 32.

As it is important that cutting disk 32 be provided with a keen edge at all times, I provide an emery wheel 100 mounted on a shaft 101 which is journaled in a bifurcated bearing 102 and rotated by means of a belt 103 encircling a pulley 104 fixed to shaft 101 between the upper and lower parts of bearing 102. Belt 103 is led over a pair of deflector pulleys 105 rotatably mounted on an arm 106 and thence around pulley 21 on shaft 18. Arm 106 is rockably mounted on a bracket 107, secured to the rear face of frame 16, and may be rocked by means of a handle 108 formed integral with arm 106 and held in selected positions by means of a toothed member and latch arrangement 109.

When it is desired to operate emery wheel 100, handle 108 is raised which will cause arm 106 to move outwardly and downwardly and bring pulleys 105 in engagement with belt 103, thus putting tension on the belt and causing it to rotate pulley 104. Shaft 101 is mounted at an angle to spindle 30 so that the edge of the emery wheel will grind the edge of cutting disk 32 to the proper bevel. Emery wheel 100 may be brought into and out of contact with cutting disk 32 by means of an adjusting screw 110 rotatable in a support 111 which is rotatably mounted on shaft 101 and held against axial movement thereon by collars 112 fixed to shaft 101 and disposed at

either side of support 111. Adjusting screw 110 is threaded into bearing 102 and has a collar and a hub disposed at either side of support 111 so that turning the adjusting screw will raise or lower support 111 and consequently bring emery wheel 100 into or out of contact with cutting disk 32.

While I have described the principle of my invention relative to particular form, it 10 will be understood that modifications may be made without departing from the spirit thereof, and hence I do not limit myself to the precise construction set forth, but consider that I am at liberty to make such 15 changes and alterations as fairly come within the scope of the appended claims.

I claim:—

1. A skiving machine including a frame, a cutting disk rotatably mounted in the frame, 20 a supporting wheel rotatable below and at right angles to the axis of the disk, a feed roller rotatable adjacent the supporting wheel, and means for adjusting the supporting wheel and feed roller longitudinally of 25 their axes.

2. A skiving machine including a frame, a spindle rotatable in the frame, a knife, having a movable cutting edge, secured to the spindle, a supporting wheel rotatable in 30 close proximity to the cutting edge, a feed roller rotatable adjacent the supporting wheel, a guard bearing on the spindle, means secured to the bearing for moving the knife toward and from the supporting wheel, and 35 a knifeguard supported by the bearing and movable with the knife.

3. A machine for skiving leather including 40 a frame, a cutting disk rotatable in the frame, a supporting wheel rotatable in close proximity to the edge of the cutting disk, a feed roller adapted to feed leather over the supporting wheel and against the edge of the cutting disk, means for raising and lowering the disk, a guard beneath the disk and movable therewith, and means for adjusting the supporting wheel and feed roller longitudinally of their axes.

4. A machine for skiving leather including 45 a frame, a cutting disk rotatable in the frame, a supporting wheel rotatable below and at right angles to the edge of the cutting disk, a feed roller adapted to feed leather over the supporting wheel and against the edge of the cutting disk, and means for adjusting the supporting wheel and feed roller longitudinally of their axes.

5. A machine for skiving leather including 50 a frame, a cutting disk rotatable in the frame, a supporting wheel rotatable in close proximity to the edge of the cutting disk, a bearing mounted on the frame adjacent the supporting wheel, a driven feed roller rotatable in the bearing, and a guide on the bearing adapted to bend the leather over the edge of 55 the supporting wheel.

6. In a skiving machine having a frame, a cutting disk rotatable therein and a supporting wheel rotatable adjacent the edge of the cutting disk, a bearing mounted on the frame adjacent the supporting wheel, a 70 guiding face formed on the bearing, a guide mounted on the bearing and overlapping the outer face of the supporting wheel, and a driven feed roller rotatable in the bearing.

7. In a skiving machine having a frame, a cutting disk rotatable therein and a supporting wheel rotatable adjacent the edge of the cutting disk, a bearing mounted on the frame adjacent the supporting wheel, a guiding face formed on the bearing, a guide mounted 80 on the bearing and overlapping the outer face of the supporting wheel, a stop on the bearing aligning with the guiding face, and a driven feed roller rotatable in the bearing.

8. In a skiving machine having a frame, a cutting disk rotatable therein and a supporting wheel rotatable adjacent the edge of the cutting disk, a bearing mounted on the frame adjacent the supporting wheel, a guiding face formed on the bearing, a guide mounted 90 on the bearing and overlapping the outer face of the supporting wheel, a driven feed roller rotatable in the bearing, means for raising and lowering the feed roller, and means for limiting the downward movement thereof.

9. In a skiving machine having a frame, a cutting disk rotatable therein and a supporting wheel rotatable adjacent the edge of the cutting disk, a bearing pivoted on the frame, a bearing bolted to the frame, a shaft rotatable in said bearings, a feed roller fixed on the shaft in close proximity to the supporting wheel, a loose cap on the bolted bearing whereby the shaft may move transversely thereof, a spring engaging the loose cap and tending to hold said shaft against transverse movement, and means for rotating the shaft.

10. In a skiving machine having a frame, a cutting disk rotatable therein and a supporting wheel rotatable adjacent the edge of the cutting disk, a bearing pivoted on the frame, a bearing adjustably bolted to the frame, a shaft rotatable in said bearings and slidable in the pivoted bearing, a feed roller fixed on the shaft adjacent the supporting wheel, and means on the shaft and bolted bearing for holding them in fixed relation axially of one another.

11. In a skiving machine having a frame, a cutting disk rotatable therein and a supporting wheel rotatable adjacent the edge of the cutting disk, bearings on the frame, a roller shaft rotatable in the bearings, a feed roller fixed on one end of the roller shaft adjacent the supporting wheel, a universal joint on the other end of the shaft, a bearing rockably mounted on the frame, a pulley shaft rotatable in the rockable bearing and 120

- having one end connected to the universal joint, a pulley on the other end of the pulley shaft, and means for raising and lowering the pulley.
12. In a skiving machine having a frame, a cutting disk rotatable therein and a supporting wheel rotatable adjacent the edge of the cutting disk, bearings on the frame, a roller shaft rotatable in the bearings, a feed roller fixed on one end of the roller shaft adjacent the supporting wheel, a universal joint on the other end of the shaft, a bearing rockably mounted on the frame, a pulley shaft rotatable in the rockable bearing and having one end connected to the universal joint, a pulley on the other end of the pulley shaft, a rod hinged to the rockable bearing, a spring encircling the rod and tending to hold said rockable bearing in its uppermost position, and a pedal for actuating said rod.
13. A machine for skiving leather including a frame, a cutting disk rotatable in the frame, a supporting wheel rotatable adjacent the edge of the cutting disk, and a feed roller adapted to feed leather over the wheel and against the edge of the disk, said feed roller and supporting wheel being axially adjustable.
14. A machine for skiving leather including a frame, a cutting disk rotatable in the frame, a supporting wheel rotatable adjacent the periphery of the wheel, and a feed roller cooperating with the supporting wheel to feed leather to the disk, said cutting disk being angularly adjustable relative to the supporting wheel, and said supporting wheel being horizontally adjustable relative to the cutting disk.
15. In a skiving machine having a base, a frame, a cutting disk rotatable in the frame, and a feed roller rotatable adjacent the edge of the cutting disk, a bearing pivoted on the frame, a post on the base, a bearing slideable in the post, a shaft rotatable in said bearings, a supporting wheel on the shaft and disposed below the feed roller and cutting disk, and means for raising and lowering the sliding bearing.
16. In a skiving machine having a base, a frame, a cutting disk rotatable in the frame, and a feed roller rotatable adjacent the edge of the cutting disk, a bearing pivoted on the frame, a post on the base, a bearing above the post, a neck formed on the bearing and slideable in the post, a shaft rotatable in said bearings, a supporting wheel on the shaft and disposed below the feed roller and cutting disk, a cam shaft rockable in the post and supporting the neck, and means for rocking the cam shaft.
17. In a skiving machine having a base, a frame, a cutting disk rotatable in the frame, and a feed roller rotatable adjacent the edge of the cutting disk, a bearing pivoted on the
- frame, a post on the base, a bearing above the post, a neck formed on the bearing and slideable in the post, a shaft rotatable in said bearings, a supporting wheel on the shaft and disposed below the feed roller and cutting disk, a cam shaft rockable in the post and supporting the neck, a crank on the cam shaft, a lever hinged to the crank and pivoted on the base, a rod hinged to the other end of the lever, and a pedal connected to the rod for raising and lowering same.
18. In a skiving machine having a base, a frame, a cutting disk rotatable in the frame, and a feed roller rotatable adjacent the edge of the cutting disk, a bearing pivoted on the frame, a post on the base, a bearing above the post, a neck formed on the bearing and slideable in the post, a shaft rotatable in said bearings, a supporting wheel on the shaft and disposed below the feed roller and cutting disk, a cam shaft rockable in the post and supporting the neck, a crank on the cam shaft, a lever hinged to the crank and pivoted on the base, a rod hinged to the other end of the lever, a pedal connected to the rod for raising and lowering same, and a spring connected to the post and to the neck for drawing said neck downwardly, the lever, crank and cam being so designed that the supporting wheel will remain in its uppermost position against the action of said spring.
19. In a skiving machine having a base, a frame, a cutting disk rotatable in the frame, and a feed roller rotatable adjacent the edge of the cutting disk, a bearing pivoted on the frame, a post on the base, a stem slideable in the post, a bearing above the post, a neck formed on the bearing and tilttable in the stem, a shaft rotatable in said bearings, a supporting wheel on the shaft and disposed below the feed roller and cutting disk, a cam shaft rockable in the post and supporting the stem, and means for rocking the cam shaft.
20. A machine for skiving leather including a frame, a cutting disk rotatable in the frame, a supporting wheel rotatable adjacent the edge of the cutting disk, pedal operated means for raising and lowering the supporting wheel, a feed roller adapted to feed leather over the supporting wheel and against the cutting disk, and means including a pivot pin and a slot and a bolt permitting tilting of the cutting disk and for securing the same in tilted position.
21. In a skiving machine having a frame with a vertically movable supporting wheel and a feed roller rotatable therein, a pin in the frame, a bearing support mounted on the pin and swingable parallel to the axis of the supporting wheel independently of the movement of the supporting wheel, means for securing the bearing support in selected positions, a bearing secured to the support, a spindle in the bearing, a cutting disk on the spindle, and means for rotating the spindle.

22. In a skiving machine having a frame with a vertically movable supporting wheel and a feed roller rotatable therein, a bearing on the frame, a spindle rotatable in the bearing, a cutting disk on the spindle, a guard bearing journaled on the spindle, a collar fixed on the spindle and abutting the guard bearing, and an adjusting screw rotatable in the guard bearing and engaging the spindle bearing whereby the cutting disk may be moved toward and from the supporting wheel. 10
23. A machine for skiving leather including a frame, a skiving tool operably mounted in the frame, a supporting wheel rotatable adjacent the skiving tool, a feed roller above the supporting wheel, said roller and wheel being so related to each other and to the tool as to be adapted to feed leather over the wheel to the tool, and means for moving the wheel to bring leather placed thereon into contact with the feeding roller, said wheel and roller being both axially adjustable transversely of the cutting position of the skiving tool. 20
24. A machine for skiving leather including a frame, a skiving tool operably mounted in the frame, a supporting wheel rotatable adjacent the skiving tool, a feed roller above the supporting wheel, said roller and wheel being so related to each other and to the tool as to be adapted to feed leather over the wheel to the tool, a pedal operated cam and a housing for the cam, and a supporting stem for the wheel extending into the housing and resting on the surface of the cam for moving the wheel vertically to and from said roller. 30
25. In a machine for skiving leather having a skiving tool, a supporting wheel and a roller adapted to be brought into contact with the leather for feeding the same to said skiving tool, the elements being so mounted as to provide open spaces on both sides of the wheel adjacent to and under the skiving tool whereby the leather may be turned on the supporting wheel at the will of the operator. 40
26. In a machine for skiving leather having a skiving tool, a supporting wheel and a roller adapted to be brought into contact with the leather for feeding the same to said skiving tool, the elements being so mounted as to provide open spaces entirely around the front, sides and back of the supporting wheel adjacent and beneath the plane in which the leather is fed between the supporting wheel and the roller. 50
27. In a machine of the character described a skiving tool, a supporting wheel and a feed roller cooperating therewith to feed leather to said tool, a guiding abutment associated with said wheel, said roller being so constructed as to force the edge of the leather over against said abutment during the feed- 60
- ing operation of said roller and a foot positioned adjacent the wheel. 70
28. In a machine of the character described, a skiving tool, a supporting wheel and a roller for feeding leather to said tool, and a foot adjacent said wheel positioned so that an aperture in the leather, the edges of which are being skived may be hooked over said foot. 75
29. In a machine of the character described, a skiving tool, a supporting wheel and a roller for feeding leather to said tool, a foot adjacent said wheel positioned so that an aperture in the leather, the edges of which are being skived may be hooked over said foot, and an abutment adjacent said wheel for guiding the leather, said roller being constructed as to its periphery to force the edge of the leather against said abutment. 80
30. A machine for skiving the edges of apertures in leather, including a skiving tool, means for feeding leather to said tool, a guide for limiting lateral movement of the said leather while being so fed, means for forcing the leather against said guide while being fed, and means to limit the feeding of the leather toward the skiving tool beyond the ends of the edges of the apertures. 85
31. A machine for skiving the edges of apertures in leather, including a skiving tool, means for feeding leather to said tool, a guide for limiting lateral movement of the said leather while being so fed, means for forcing the leather against said guide while being fed, and means to limit the feeding of the leather toward the skiving tool beyond the ends of the edges of the apertures, the machine being provided with a clear open space around the feeding means in the region immediately below the skiving tool. 90
- In testimony whereof I have signed my name to this specification. 95
